Application March 15, 1940, Serial No. 324,032

11 Claims. (Cl. 93—51)

This invention relates to an improved method and apparatus for forming cartons, particularly paperboard cartons, and although not restricted in all respects to employment with cartons in which certain portions are secured by means of thermoplastic adhesive material, is directed in some aspects to the formation of such cartons.

The main objects of the invention are to provide an improved method and apparatus for forming cartons from prefabricated carton blanks; to provide an improved method and apparatus for folding and securing in receptacle form prefabricated blanks provided with adhesive material on predetermined portions of the blanks; to provide an improved method and apparatus for folding into receptacle form prefabricated carton blanks having thereon dried thermoplastic material which becomes soft and tacky when subjected to heat; to provide an apparatus of the character indicated means for effectively softening thermoplastic adhesive material without danger of scorching or burning the material of the carton blank which carries the thermoplastic material; to provide a method and apparatus of the character indicated which will operate at relatively high speed and relatively quietly; and in general it is the object of the invention to provide an improved method and apparatus for folding into receptacle form prefabricated carton blanks.

Other objects and advantages of the invention will be understood by reference to the following specification and accompanying drawings (5 sheets) wherein there is illustrated apparatus embodying a selected form of the invention and capable of performing the improved method of forming cartons.

In the drawings:

Figure 1 is a plan except that the right-hand end portion of the mechanism is shown in section as indicated by the line 1—1 of Figure 3;

Figure 2 is a section on the line 2—2 of Figure 1;

Figure 3 is a side elevation of the right-hand end portion of the mechanism illustrated in Figure 1;

Figure 4 is a section on the line 4—4 of Figure 3;

Figure 5 is a perspective of a detail of construction also appearing in Figure 4.

Figure 6 is a section on the line 6—6 of Figure 1;

Figure 7 is a section on the line 7—7 of Figure 6;

Figure 8 is a perspective of a carton blank

typical of the blanks which the apparatus illustrated is adapted to fold into receptacle form;

Figure 9 is a perspective of a receptacle formed by the method and apparatus herein referred to from the blank illustrated in Figure 8;

Figures 10 and 11 are perspectives illustrating different positions of the folding mechanism; and

Figure 12 is a section on an enlarged scale on the line 12—12 of Figure 4.

Referring now to the drawings, the carton blank which the disclosed apparatus is designed to fold into receptacle form is formed of a suitable weight of paper or cardboard and comprises a generally rectangular member provided with creasing indicated by broken lines indicated at 15 to divide the blank into a bottom-forming portion 17, side wall forming portions 18, 18, corner-forming portions 19, 19 which extend integrally from the ends of the side wall portions 18 and are foldable along the crease lines 15, and end wall forming portions 20, 20.

The end wall portions 20, 20 are provided on their inner faces with adhesive material as indicated at 21, the same being preferably of a suitable thermoplastic composition which when dry is hard and free from tackiness at ordinary temperatures. The thermoplastic adhesive material is to be selected with regard to the kind of material to be packaged in the receptacle, for example, if the product to be packaged is cheese or other materials which are flown into the receptacle in more or less liquid form at high temperature, then the thermoplastic material should be such that it will not become soft or lose its adhesive properties until it is heated to a substantially higher temperature than that of the heated food product. Also, the material should be of such a character that it will not impart any flavor to the product packaged. Various thermoplastic materials may be produced which meet such requirements and they are considered preferable to conventional wet adhesives for many reasons well known to those skilled in the art.

As indicated in Figure 9, the side walls 18, 18 are folded to upwardly extending, right-angular relation to the bottom wall 17, the corner forming flaps 19, 19 are then folded inwardly from the respective side walls and the end walls 20, 20 are then folded upwardly into wall-forming position overlapping the outside of the said corner-forming flaps 19. The adhesive material 21, if of thermoplastic character, is preliminarily heated so as to render it soft and tacky so that when the end wall portions 20, 20 are folded upwardly and pressed against the flaps 19, 19, said

adhesive material will serve to secure the contacting parts permanently in the said relation.

The thermoplastic adhesive material may be permitted to cool naturally while the overlapping parts are held in set-up relation but to enable the apparatus to be operated at a high speed and without excessively lengthening the mechanism to hold the carton in set-up condition, means is provided in the described apparatus for chilling the adhesive material when the blank is formed to receptacle condition as shown in Figure 9.

The mechanism herein disclosed comprises at its left-hand end as viewed in Figure 1, an arrangement such as a hopper designated 22 for receiving a stack of blanks of the type illustrated in Figure 8, the same being then in flat condition, having thereon the thermoplastic adhesive material indicated at 21. The blanks are fed one by one by suitable feeding mechanism not herein shown but such as shown, for example, in Patent No. 1,979,253 to Coy, for delivering the blanks one by one to a conveyor which propels the blanks to the folding mechanism. Such a conveyor is shown herein as comprising a pair of endless chains 23, 23, the same being supported by suitably mounted sprockets such as indicated at 24.

The conveyor chains 23, 23 are continuously driven in unison and at a constant speed by a suitable driving connection with a main power shaft indicated at 25, such connection including, for example, a chain 26 which extends around a sprocket carried by the power shaft 25, a sprocket carried by the shaft 27 which carries the conveyor chain sprockets at one end of the conveyor, and a sprocket carried by a shaft 28 as best shown in Figure 3. The conveyor chains 23 are provided with suitable upwardly projecting ears or dogs 29, which are adapted to engage the rear edge of a carton blank so as to propel the same in unison with the movement of the conveyor chains 23, 23.

The carton blanks are guided in their travel on the conveyor chains 23, 23 by means of angle iron side members 30, 30, the horizontal flanges of which serve to support the opposite end portions of the blanks, and the vertical upstanding flanges of which serve to prevent sidewise shifting of the blanks. A centrally disposed bar-like member 31 serves to support the carton blanks intermediate the conveyor chains 23, 23.

While the blanks are being propelled by the conveyor mechanism, the thermoplastic adhesive material carried by portions of the blanks is subjected to heat for softening the material to a suitable tacky condition. For this purpose it is preferred to avoid direct contact with either the carton blank stock or the thermoplastic material and means is provided for directing heat by radiation to the material to be softened. In this instance, such means comprises two or more elongated electrical resistance heating elements located at each side of the conveyor above the path of travel of the opposite end portions of the carton blanks. Various forms of electrical resistance units may be employed and in this instance I contemplate the use of commercially available carbon rod devices which embody a carbon composition heating element 32 mounted in a suitable refractory body 32', so formed that it will reflect in the desired direction heat generated by the carbon rod 32.

Such units are designated in their entirety 33 and each is mounted independently of the other so as to be vertically adjustable relative to the

path of travel of the carton blanks. For this purpose, the said heating devices 33 are secured to the upper ends of straps designated 34, the lower ends of which are suitably slotted and clamped by means of bolts or cap screws 35 to a conveniently accessible frame part 36 which serves also to support the conveyor structure. It will be apparent that by varying the space between the heating devices 33 and the path of travel of the carton blanks a desirable control of the heating effect of the devices is provided. Furthermore, by providing two or more independently controllable electric units at each side of the structure, one or more of the units may be 10 shut off, thereby affording further control of the adhesive softening operation of the mechanism.

Although the heating operation is, at present, preferably effected by the means described, such means is not essential. Other heating means 20 may be substituted. For example, heat may be applied by means of plates or shoes heated by any medium which will produce the required temperature. Such plates may, if desired, be positioned on the side of the blanks opposite the side on 25 which the adhesive is applied, thereby to avoid any possibility of direct contact with the adhesive material, or they may be mounted so as to be closely adjacent but in sufficiently spaced relation to the adhesive bearing side of the carton 30 blanks to avoid contact with the adhesive if such contact is to be avoided. However, in some cases a wiping contacting arrangement may be preferable for various reasons.

The heating operation may also, for example, 35 be effected by means of a current or blast of hot air directed over or against the adhesive bearing portions of the carton blanks.

It may be observed that the softening operation 40 is dependent not only upon the temperature generated by the heating devices, the distance thereof from the material to be heated, the length of the heating device, and similar variables of the selected heating device, but also upon the speed of travel of the carton blanks past said heating devices. The indicated variables are readily 45 adjustable, whereas the speed of travel of the conveyor and synchronized parts of the mechanism and the incidental variation in the production capacity of the apparatus involve greater difficulties, 50 either with the carton forming apparatus or with the resulting effect on other operations in the plant wherein the apparatus is relied upon for cartons to meet a given production schedule.

The heating of the carton blanks, incident to 55 the adhesive softening operation, sometimes tends to cause the blanks to curl upwardly and thereby become disengaged from the ears or lugs 29 of the conveying chains 23. To prevent or limit such curling, there are provided longitudinally extending bars 125, 125 (see Figs. 1 and 2) which overlie the path of travel of the blanks near their ends but spaced laterally from the adhesive bearing portions thereof. The number and location of the bars 125 may be varied in accordance with the requirements to control the curling effect in each case. The bars 125, 125 may be mounted in any suitable manner and in this instance they are vertically adjustably suspended from cross members such as shown at 126 which rest on the upper edges of the guide members 30, 30. The cross members may be free of attachment to the guide members so as to facilitate removal of the curl controlling structure, or they may be attached in fixed position if desired. However, one 70 practical arrangement contemplates an unat-

tached arrangement wherein the cross members are provided with shoulders such as 127 for positioning the structure transversely of the path of travel of the carton blanks. For adjustably supporting the bars 125, 126, the latter are suspended from the cross members by means of screws such as appear at 128, suitable springs 129 being provided for urging the bars to their lowest position as determined by the screws.

The conveyor chains 23, 23 deliver the carton blanks with the thermoplastic material thereon in tacky condition to folding mechanism which comprises a stationary outer forming member or die, and a series of inner forming members or mandrels designated 37 which are carried in predetermined spaced relation by endless conveyor chains 38, 38 and connecting bars 38'.

The conveyor chains 38, 38 extend around suitably journaled upper and lower sprockets 39 and 40, respectively, and they are continuously driven by means of intermeshing gears designated 41 (Figs. 1 and 3) carried by the power shaft 25 and the shaft on which the lower sprocket 40 is mounted. The travel of the inner form members 37 is guided at least in their operative zone by means of channel-like guide members 95, 95 in which the ends of the connecting bars 38' travel. Said channel-like members are carried by frame parts such as indicated at 91, 91 (see Fig. 1).

The inner forming members 37 are of generally rectangular form and of such size in cross-section that they will fit snugly within the cartons which are folded thereon. They are connected to the conveyor chain by means of relatively narrow ears 42 which are disposed rearwardly from the leading ends 43 of the inner form members.

The outer form or die comprises a transversely extending plate member 44 at one side, and a pair of transversely spaced plate members 45 and 46 at the opposite side. The upper ends of the said plates 44, 45 and 46 are disposed in alignment with the surface of a table plate 47 over which the carton blanks are received from the conveyor 23. For properly locating the carton blanks, one of which is indicated at B in Figure 6, over the ends of the forming plates 44, 45 and 46, there are provided extensions 48 of the side guide flanges 30, 30 and an abutment or stop 49 spaced outwardly from the forming plates 45 and 46.

For effecting delivery of the carton blanks to the stop 49, there is provided a reciprocating feeding device comprising a finger 50 pivotally mounted as shown at 51 on the lower end of an arm 52 which is mounted on a cross shaft 53, which in turn is pivotally mounted in suitable upright frame or bracket part such as indicated at 54. The shaft 53 has connected to it an arm 55 which is connected by a link 56 to a crank pin 57 carried by the continuously driven shaft 27.

A spring 58 or other suitable means is provided for normally urging the finger 50 to rock in a clockwise direction about its pivot mounting 51 on the lower end of the arm 52, and the outer or free end of said finger is adapted to ride in a groove 59 which is provided in the table plate 47. The free end of said finger 50 is further provided with an upwardly and forwardly extending ear 60 which insures proper engagement of the edge of the carton with the end of the finger 50 from which said ear extends.

It will be apparent that incident to the rotation of the crank 51, the finger 50 will be reciprocated. In its rearward or counter-clockwise movement as viewed in Figs. 3 and 6, said finger will ride over a carton being advanced by the

conveyor 23 until the free end of the finger drops behind the carton blank. Upon its return or forward movement, the finger will take up the feed movement of the carton blank and advance it to predetermined position against the stop 49.

One of the inner form members 37 next approaches the carton blank disposed over the outer forming member plates 44, 45 and 46 and serves, incident to its entrance between the plates, to fold the blank into U-shape form in which the side walls 18, 18 extend upwardly relative to the bottom wall 17 which is then disposed against the bottom or leading end 43 of the inner forming member.

Incident to such upward folding of the side walls 18, 18, the corner-forming flaps 19, 19 are also folded upwardly and they are next subjected to a folding operation which turns inwardly into the position illustrated in Figure 9. Such inward folding is effected by means of folding members 61 and 62, respectively, pivotally mounted on the adjacent sides of the outer forming member and provided near their upper ends with folding ears 63 arranged to engage the corner flaps 19 of the carton blank at the opposite ends of each of the side walls 18, 18.

Said folding members 61 and 62 are simultaneously actuated in opposite directions by means of a cam 64 carried by the power shaft 25 and operating against a roller 65, carried by one arm of a pivoted bell crank 66, the other arm of which is connected by means of a link 67 to an arm 68 which is secured to a shaft 69 which carries the flap-folding member 61.

The shaft 69 is interconnected with the shaft 70 which carries the folding device 62 by means of arms 71 and 72 and a link 73 as best shown in Figure 3. A spring 74 or other means may be provided for causing the cam-following roller 65 to maintain contact with the periphery of the cam 64.

To prevent interference by the end wall portions 20, 20 of the carton blank with the folding movement of the corner flaps 19, 19, said end walls 20, 20 are temporarily deflected to a downwardly inclined position as illustrated in Figure 11. The means for so deflecting the end wall portions 20 comprises rods 75, 75 which are aligned vertically with the normal position of the end wall portions of the carton blank when in operative relation to the forming dies. Said rods are carried by members indicated at 76 which are rigidly secured to a cross shaft 77, the latter being rotatably mounted in the adjacent ends of arms such as 78 which are pivotally mounted at their opposite ends as indicated at 79 in portions of the frame members 54 provided for that purpose.

One of the arms 78 has connected to it through its pivot shaft 79, an arm 80 which is provided at its opposite ends with a roller 81 for engaging a rotary cam 82 carried by the driven shaft 21. The weight of the arms 80 and 78 and parts carried by their outer ends urges the arm to swing downwardly in a clockwise direction, causing the roller 81 to maintain operative engagement with the cam periphery 82, so that incident to rotation of the cam 82 said arms 80 and 78 and the parts carried thereby are oscillated, the rods 75 being thereby reciprocated in a vertical direction. To maintain the rods 75 in a substantially vertical position at all times, the shaft 77 has rigidly secured to it a link 83 which extends upwardly and is pivotally connected as shown at 84 to the

adjacent free ends of arms 85 which are in turn mounted on a shaft 86 which is suitably pivotally mounted in portions of the frame member 84 provided for that purpose. It will be apparent that the parallel arm arrangement 85 and connections therebetween serve to maintain the deflecting rods 75 in substantially vertical position at all times.

It will be further observed that rocking movement is transmitted from the cam 82 to the arm 80, through the adjacent arm 78 and link 83 to the immediate overlying arm 85 and thence through the shaft 86 to the arm 85, link 83 and arm 78 at the other side of the apparatus.

It being understood that the various cams and operating elements referred to are properly timed in their operation, it will be apparent that the cam 82 is so adjusted and formed as to cause the depressing rods 75 to move downwardly to deflect the carton blank end portions 20, 20 as shown in Figure 11, just prior to the time the cam 64 actuates the folding devices 61 and 62. Adjustment of the extent of deflection of the carton end wall portions may be made by adjusting the vertical position of the rods 75, 75 in the holders 76, by modifying the cam 82, or by other well known means. The timing of the operation of the deflecting members 75, 75 and the folding members 61 and 62 is so adjusted that these parts operate immediately after the side wall portions 18, 18 are folded upwardly on the side walls of the inner forming member 37 and during the continued travel of the same.

The space between the folding plates 45 and 46 through which the inner form member connecting element 42 passes is not of sufficient width to seriously hinder the folding of the side wall 18 of the carton since the carton blanks are creased to facilitate such folding. However, it is preferred that means be provided for keeping the upper folding edge between said plates 45 and 46 and for such purpose there is provided a movable member 87, the upper edge of which is adapted to be aligned with the upper edges of the members 45 and 46 and which member 87 is of such size as to fit between said plates 45 and 46 as best shown in Figures 10 and 11. The thickness of the member 87 is also such that when the member is in operative position shown in Figures 10 and 11, its inner face is substantially flush with the inner faces of the members 45 and 46.

The member 87 is carried by an arm 88 which is pivotally mounted at one end as indicated at 89 in suitable lugs extending from a cross-member 80 which is carried by frame parts 91, 91 of the apparatus (see Figures 1 and 6). Intermediate its ends, the arm 88 is provided with a roller 92 which is adapted to engage a cam 93 carried by the rotatably driven shaft 28. The cam 93 is so shaped and it is driven in such timed relation to the operation of the mechanism that the member 87 will be moved into operative relation with the folding plate members 45 and 46 before the inner forming member 37 reaches its operative relation to the folding structure and so that the member 87 is withdrawn in ample time to permit the connecting neck or ear 42 and other parts to travel downwardly through their normal path of movement. A spring 94 or other suitable means is provided for causing the cam-following roller 92 to maintain operative contact with the cam 93.

The outer die or forming member is also 75

equipped with means for folding upwardly the end wall portions 20, 20 into overlapping relation on the outside of the flaps 19, 19, such devices being caused to operate incident to the downward movement of the partially folded blank on the end of the inner member 37.

Said end wall folding devices comprise the upper ends 96, 96 of plate members 97, 97, which extend transversely between depending extensions of the side folding plates 44 and 45, 46, the upper ends of which plates constitute the means for effecting upward folding of the side wall portions 18, 18 of the carton blank. It will be apparent that when the inner forming member 37 carries the carton blank downwardly between the upper ends of the plates 97, 97, the end walls 20, 20 of the carton blank will be folded upwardly into overlapping relation to the previously in-folded flaps 19, 19.

The plates 97, 97 at opposite ends of the path of travel of the folded carton blank or receptacle may be disposed in such position that they press the end walls 20, 20 into tight contact with the underlying flaps 19, 19 so as to produce an effective bond between the overlapping parts through the agency of the reactivated thermoplastic adhesive material. However, the application of pressure in such a manner would create a serious drag against the advancing movement of the inner form member with the receptacle thereon, and the action incident to such a drag is somewhat objectionable for other reasons. In this instance there is provided a series of pressure rollers respectively designated 98 for cooperation with each end of the inner form member 37. Said pressure rollers are journaled as indicated at 99 in suitable brackets 100 (see Figures 4, 7 and 10) and each bracket 100 is pivotally mounted as indicated at 101 in the adjacent side members 44, 45 and 46.

The axis of the pivotal mounting 101 is in eccentric relation to the axis of the journal mounting 99 of each roll, so that rocking movement of the respective brackets 100 about their pivot mountings will effect movement of the respective rollers toward or from the adjacent sides of the inner forming member 37. For the purpose of urging the rollers 98, 98 toward the adjacent sides of the inner form member 37, 50 springs such as indicated at 102 are provided, such springs being interposed between adjacent arms 100 which are arranged in reversed relation to each other as clearly shown in Figure 4, so that expansion of the springs 102 serves to cause the adjacent brackets 100 to rock in such a direction that their respective rollers 98 are urged toward the inner forming member 37. Adjustable means for limiting the extent of such inward movement may be provided in the form of adjustable set screws 103 which are adapted to engage suitably provided frame or other portions such as indicated at 104.

It will be apparent that the rollers 98 successively engage the receptacle formed on the leading end of the inner form member and it will be understood that the pressure applied by the rollers may be adjusted to suit any particular carton structure by the selection and insertion of springs 102 of the desired strength.

During the travel of the receptacle between the pressure rollers 98, 98, the softened thermoplastic adhesive remains in sufficiently plastic condition to permit the pressure rollers to squeeze the overlapping carton portions tightly together. To insure permanence of the bond effected by

the thermoplastic adhesive material, it is preferred that the same be chilled before the overlapping carton portions are relieved from all pressure. For this purpose there are provided chilling shoes or blocks 105, 106 respectively associated with the opposite series of pressure rollers 98, 99 (see Figures 4 and 12). Each such shoe has its inner face finished to such smoothness as to avoid the creation of too much drag on the moving receptacle carried by the inner forming member 37 and the receiving ends of said shoes are relieved as indicated at 106, so as to facilitate entrance of the form-carried receptacle between the shoes.

Each shoe 105 is mounted between the respectively adjacent side plates 44, 45 and 46 for movement bodily toward and from the path of travel of the inner forming member. For this purpose there are provided links such as indicated at 107, 107, at opposite sides of each shoe, such links being pivotally mounted as indicated at 108, 108 at their upper ends in the said side plates 44, 45 and 46 and having their lower ends pivotally connected as indicated at 109, 109 to the shoe intermediate its upper and lower ends. A spring 110 is interposed between each shoe 105 and another frame or similar portion 111, such spring serving to normally urge the shoe to move inwardly toward the path of travel of the inner forming member 37. The extent of such inward movement may be limited by suitable adjustable stop screws 112, 112 which are threaded into the respective shoes and fit slidably through suitable openings in said frame portions 111.

For cooling the shoes 105, they are provided with suitably formed internal passageways such as indicated at 113 which are provided with inlet and outlet conduits 114, 114, whereby water or other cooling medium may be circulated through the said passageways. The conduits 114, 114 may include at some suitable point a flexible hose or other connection which will permit free movement of the shoes inwardly and outwardly.

When the inner forming member 37 with a receptacle formed thereon emerges from between the cooling shoes 105, 105, the receptacle is ready to be stripped from the inner forming member 37, the thermoplastic adhesive material having then been set sufficiently to maintain the receptacle in its set-up condition.

For stripping the receptacles from the inner forming member 37, there are provided in association with the opposite sides of the inner forming member 37, endless chain or belt conveyor members 115, 115 which are carried by suitable means such as upper and lower sprockets 116 and 117, respectively, such sprockets being suitably rotatably mounted in frame parts as best shown in Figures 3 and 4 of the drawings.

The conveyors 115, 115 are so arranged that one reach of each conveyor travels downwardly in outwardly spaced but substantially parallel relation to the travel of the respectively adjacent sides of the inner forming member 37 and they are continuously driven at a speed of travel which is substantially higher than the speed of travel of the inner forming member 37. Each conveyor is provided with a suitable resilient finger 118 having a laterally extending head or lip 119 at its upper end which is adapted to engage the upper edge 120 of the respectively adjacent end walls of the receptacle on the inner forming member. Each of said fingers 118 is so arranged that the inner ends of their respective lips 119 will first engage the adjacent sides of the inner

form 37 somewhat above the said edges of the end walls of the receptacle and incident to the higher speed of travel of the conveyors 115, 115, the lips of said fingers will engage said receptacle edges and ultimately pull the receptacle from the end of the inner forming member 37. The receptacle, of its own weight, will drop from between the fingers 118, 118 and may be received by a conveyor or other preferred means.

For driving the conveyors 115, 115, there is provided a shaft 121 suitably journaled in the frame work of the apparatus and connected by pairs of bevelled gears indicated at 122, 122 to the shafts 123 which carry the lower sprockets 117. The shaft 121 is in turn driven by a chain 124 which engages suitable sprockets carried by the shaft 121 and another driven shaft such as the shaft 27. The speed at which the conveyors 115, 115 are driven may be determined by proper selection of sprockets which cooperate with the chain 124 and by proper selection of the intermeshing gear pairs 122, 122. In this instance, the sprocket on the shaft 121 which is driven by the chain 124 is of much smaller pitch diameter than the driving sprocket on the shaft 27, so that the speed of rotation of the shaft 121 is increased to effect the desired result.

The described apparatus, being continuous in operation and being free from noisy operating reciprocating mechanism, is both rapid and quiet in operation. Because of its improved arrangement for applying pressure to the overlapped parts of the receptacle, it has been found to be highly efficient in the forming of cartons which employ thermoplastic adhesive material for effecting the bond between such overlapping parts and its arrangement for chilling the adhesive material to set the same after the extended application of pressure contributes materially to its successful operation.

Although the apparatus as shown is arranged for setting up prefabricated carton blanks, it will be apparent to those skilled in the art that instead of providing mechanism for feeding such prefabricated blanks, mechanism for forming such blanks may be substituted, such mechanism then including means for applying the thermoplastic adhesive material to the selected portions of the carton blanks. In such a case, the employment of the heating units 33 may possibly be dispensed with, although even in such case they may be desirable for the purpose of maintaining the adhesive material in its most desirable tacky condition until the carton blank reaches the folding elements of the apparatus.

Many changes in the structure may be made without departing from the spirit of the invention, the scope of which should be determined by reference to the following claims, the same being construed as broadly as possible, consistent with the state of the art.

I claim:

1. The method of forming a carton which comprises the steps of providing prefabricated carton blanks having thermoplastic adhesive material on predetermined portions of the blanks, propelling the carton blanks edgewise, effecting softening of the adhesive material by directing radiated heat thereto during the travel of the blanks and then, while the adhesive remains soft and tacky, folding the blanks into receptacle form and pressing together the portions thereof to be united by said adhesive.

2. Apparatus for forming cartons employing thermoplastic material for adhesively uniting

overlapped portions comprising means for propelling carton blanks having thereon dried thermoplastic material, heat radiating means disposed adjacent but in spaced relation to the path of travel of the blanks for radiating heat to said dried thermoplastic material so as to soften the same to tacky condition, means for adjustably mounting said heating means for movement toward and from said path of travel, thereby to facilitate regulation of the softening effect of said heating means, means for folding the blanks to receptacle form with predetermined portions overlapping the adhesive-bearing portions, and means for resiliently pressing together said overlapping portions.

3. Apparatus for forming cartons embodying thermoplastic material for adhesively uniting overlapped portions comprising means for propelling carton blanks having thereon dried thermoplastic material, heating means disposed adjacent the path of travel of the blanks for heating and thereby softening to tacky condition said thermoplastic material, means for folding the blanks to receptacle form with predetermined portions overlapping the adhesive-bearing portions, means for resiliently pressing together said overlapping portions, means for chilling and thereby setting the adhesive between said overlapping portions, said chilling means comprising a presser member mounted for movement toward and from the overlapped portions of the carton, means yieldingly urging said presser member toward said overlapped portions, means for limiting such movement, and said presser member being provided with a passageway therein for the circulation therethrough of a cooling medium.

4. In apparatus of the class described, means for forming and propelling cartons, mechanism for applying pressure on overlapped carton portions comprising a pair of side plates, a plurality of relatively independent brackets pivotally mounted on said side plates, a roller journaled in each of said brackets on an axis eccentric with the pivot axes of the respective brackets, spring means acting on said brackets to urge the same to rock in such direction as to urge the respective rollers against said carton portions, means for limiting the spring-effected movement of said rollers, and a pressure block for engaging said portions after the same pass said rollers, said pressure block being mounted in said side plates for movement bodily toward and from said overlapped portions, spring means for urging said block toward said overlapped portions, means for limiting the spring-effected movement of said block, and said block being provided with a passageway therein for the circulation therethrough of a heat-exchanging medium.

5. Apparatus for forming cartons comprising an outer forming member, an inner forming member adapted to move continuously in a predetermined direction through said outer member to cooperate therewith to fold wall-forming portions of a carton blank into receptacle-forming position relative to another portion of the blank, means independent of said outer member for folding corner-forming flaps of the blank into receptacle-forming position, reciprocable means movable in the direction of movement of said inner member for moving certain wall-forming portions of the blank out of the way of said flaps during the folding movement thereof, and means for folding said last mentioned portions into wall-forming position overlapping said folded flaps.

6. Apparatus for forming cartons comprising an outer forming member, an inner forming member adapted to move continuously in a predetermined direction through said outer member for cooperation therewith in folding carton blanks into receptacle-forming condition, means for propelling said inner forming member comprising a continuously propelled endless conveyor, an ear spaced rearwardly from the leading end 10 of said inner member, projecting laterally therefrom and secured to said conveyor for interconnecting said inner member and conveyor, said outer forming member being provided with a slot in a portion thereof for permitting the passage therethrough of said ear, auxiliary outer forming member means adapted to be inserted in said slot to complete said outer forming member so as to provide continuous forming surfaces for cooperation with the leading end of said inner member, means for mounting said auxiliary member for movement into and out of said slot, and means for effecting such movement of said auxiliary member in timed relation with the travel of said inner member through said outer member.
7. Apparatus for forming cartons employing thermoplastic material for adhesively uniting overlapped portions comprising means for propelling carton blanks having thereon dried thermoplastic material, heating means for softening to tacky condition said thermoplastic material, said heating means comprising two or more elongated electrical resistance devices arranged longitudinally of said propelling means so as to be 20 adapted to successively heat carton portions propelled therewith, said electrical devices being adjustably mounted in spaced relation to the path of travel of said carton blanks so as to effect softening of said thermoplastic material by heat radiated from said devices, the heating effect of said heating means being controllable by the capacity of each heating element to be turned on or off independently of the other and by the adjustability of the spacing of the heating members 30 relative to the path of travel of the carton blanks, means for folding the blanks to receptacle form with portions thereof overlapping the adhesive-bearing portions, and means for pressing together said overlapping portions.
8. Apparatus for forming cartons employing thermo-plastic material for adhesively uniting overlapping portions, comprising means for propelling carton blanks having thereon dried thermo-plastic material, an electrical resistance device arranged longitudinally of said propelling means, so as to be adapted to heat carton portions propelled therewith, so as to effect softening of said thermo-plastic material by heat radiated from said device, said electrical device being adjustably mounted in spaced relation to the path of travel of said carton blanks whereby the heating effect of said electrical device is variable by adjustment of the spacing of said electrical device relative to the path of travel of the 40 carton blanks, means for folding the blanks to receptacle form with portions thereof overlapping the adhesive-bearing portions, and means for pressing together said overlapping portions.
9. Apparatus for forming cartons employing thermo-plastic material for adhesively uniting overlapping portions, comprising means for propelling carton blanks having on portions thereof dried thermo-plastic material, an electrical resistance device extending longitudinally of said 50 propelling means and disposed in spaced relation to the path of travel of said carton blanks, means for folding the blanks to receptacle form with portions thereof overlapping the adhesive-bearing portions, and means for pressing together said overlapping portions.

to the path of travel of the blanks carried by said propelling means to effect softening of said thermo-plastic material by heat radiated from said device when energized, means for folding the blanks to receptacle form with portions thereof overlapping the softened thermo-plastic bearing portions, and means for holding together said overlapping portions while said softened thermo-plastic material sets.

10. Apparatus for forming cartons employing thermo-plastic material for adhesively uniting overlapping portions, comprising means for propelling carton blanks having on portions thereof dried thermo-plastic material, a carbon rod electrical resistance device extending longitudinally of said propelling means and disposed in spaced relation to the path of travel of the blanks carried by said propelling means to effect softening of said thermo-plastic material by heat radiated from said carbon rod device when energized, 20 means for folding the blanks to receptacle form

with portions thereof overlapping the softened thermo-plastic bearing portions, and means for holding together said overlapping portions while said softened thermo-plastic material sets.

- 5 11. Apparatus for forming cartons employing thermo-plastic material for adhesively uniting overlapping portions, comprising means for propelling carton blanks having thereon dried thermo-plastic material, heat radiating means disposed adjacent but in spaced relation to the path of travel of the blanks for radiating heat to said dried thermo-plastic material so as to soften the same to tacky condition, means for folding the blanks to receptacle form with portions thereof overlapping the adhesive-bearing portions, and means for holding together said overlapping portions while said softened thermo-plastic material sets.
